UNITED STATES PATENT OFFICE.

MARY A. WILLBRANDT, OF WASHINGTON, KANSAS.

GARMENT-FASTENER.

1,074,229.

Specification of Letters Patent. Patented Sept. 30, 1913.

Application filed June 24, 1912. Serial No. 705,657.

To all whom it may concern:

Be it known that I, MARY A. WILLBRANDT, a citizen of the United States, residing at Washington, in the county of Washington 5 and State of Kansas, have invented certain new and useful Improvements in Garment-Fasteners, of which the following is a specification, reference being had to the accompanying drawings.

10 This invention relates to placket fasteners and has for its primary object to provide complementary fastening members upon the opposite sides of the placket whereby the same may be easily and quickly connected 15 to close the placket, and hold the same against all liability of accidental separation.

Another object of the invention resides in the provision of a fastening device for the 20 above purpose which will eliminate bulkiness, the fastening members being invisible when the placket is closed so that the proper fit and neat appearance of the dress is not detracted from.

25 Another and more specific object of the invention is to provide a series of hooks formed from a single length of wire, each of the hooks being provided with eyelets whereby the same may be sewed to one edge 30 of the placket, and a series of loops also formed from a single length of wire and adapted to be sewed to the opposite edge of the placket, said hooks and loops having co-engaging portions whereby the bills of the 35 hooks are disposed in the plane of the looped wire when the parts are connected, and oscillation of the hooks upon the loops prevented, thereby obviating liability of the bill portions being forced through the material and tearing or otherwise injuring the 40 same.

A still further object of the invention is to provide a device for the above purpose which is simple and inexpensive in construction, may be easily and quickly applied to the placket of a dress without necessitating numerous measurements, is strong and durable in construction and of great convenience in practical use.

With the above and other objects in view 50 as will become apparent as the description proceeds, the invention consists in certain constructions, combinations and arrangement of the parts that I shall hereinafter fully describe and claim. 55

For a full understanding of the invention, reference is to be had to the following description and accompanying drawing, in which—

Figure 1 is an elevation, illustrating the 60 edges of the placket opening in the dress, one of the edge portions being reversed to show the inner side thereof whereon the fastening hooks are secured. Fig. 2 is an enlarged detail fragmentary elevation showing 65 the fastening members connected; Fig. 3 is a section taken on the line 3—3 of Fig. 2; and Fig. 4 is a detail perspective view of one of the fastening loops.

Corresponding and like parts are referred 70 to in the following description and designated in the accompanying drawing by like reference characters.

Referring in detail to the drawing Fig. 1 indicates the opposite edge portions of a 75 dress placket which are adapted to be detachably connected by means of my improved fastener. In the use of the ordinary hook and eye now commonly employed, for this purpose, after a short period of use, 80 the hooks readily become detached from the eyes so that the placket will gape in places, thus detracting from the neat appearance of the dress. Pressure upon the edges of the placket will also often force the projecting bills of the hooks through the material of the dress, especially if the same is 85 of silk or other fragile material.

My improved fastener is devised for the purpose of overcoming the above noted deficiencies, and the manner in which these ends are accomplished will be clearly apparent from the following description.

5 indicates a length of wire the gage of which will vary in accordance with the quality and character of the material to which the same is to be applied. At spaced points, the wire 5 is bent upon itself to form eyes 6.

The wire is laterally projected from the eyes and then returned upon itself and bent to provide the loop or bill 7. From the bill 7 the wire is then again returned and provided with a second eye 8 which is disposed in line with the eye 6. From the eye 8, the wire is extended inwardly and is projected outwardly between the parallel laterally extending portions of the hook to form a 10 resilient tongue 9. From this resilient tongue, the wire is again bent upon itself and extended inwardly to a point between the eyes 6 and 8, from which point the wire extends longitudinally to the eye 6 of the 15 next adjacent hook. In this manner a plurality of hooks are formed in the single wire 5, and these hooks may be spaced apart as desired. The number of hooks will of course vary in accordance with the length 20 of the placket and the weight of the material. These hooks are secured upon one edge of the placket opening, preferably the left hand edge and on the inner face thereof, by sewing the eyes 6 and 8 to the material 25 in the usual manner.

To the opposite side of the placket opening and at a slight distance from the extreme edge thereof, the eyes or loops with which the hooks engage are attached. These eyes or loops are also formed from a single 30 length of wire 10, said wire being bent at intervals to provide spaced pairs of eyes 11. The wire between the eyes 11 is projected laterally and bent into substantially semicircular form to provide loops 12. The intermediate portions of these loops are offset 35 or projected in a plane at right angles to the wire 10 as indicated at 13. These projections 13 of the loops are adapted for engagement with the resilient tongues 9 formed upon the hook members in the manner above described. The wire 10 is secured to the edge of the placket by securely sewing the eyes 11 thereon.

In Figs. 2 and 3 of the drawing, I have shown the hooks engaged with the loops 12, and it will be observed from reference to Fig. 3 that when so engaged, the projections 13 of the loop 12 occupies substantially the 50 entire space between the outer end of the bill 7 and the end of the tongue 9 of the hook. Thus the bill of the hook is maintained in practically the same plane as the eyes 11 and the body of the wire 10. The projections 13 of the loops 12 engaging the extremities of the tongues 9 tend to overcome rocking or oscillatory movement of the hooks upon said loops so that the ends of the hook bills are held away from the material and liability of 55 the same being forced therethrough by pressure upon the edges of the placket is obviated. The offset portions of the wire 12 are curved inwardly and are adapted to bear 60 on the wires of the bill 7, to prevent the

medial portions 13 of the loops from moving 65 laterally with relation to the hooks thereby preventing accidental disengagement of the hooks and loops.

From the foregoing it is thought that the construction and manner of use of my improved placket fastener will be clearly understood. It will of course be obvious that while I have referred to the device as a placket fastener for convenience in describing the same, the device is also applicable 70 for various other analogous uses. By means of the same the placket of a dress may be easily, quickly and securely closed. The connected hook and loop members effectually prevent one or more of the hooks becoming 75 disconnected from the loops, thereby obviating the objectionable gaping of the placket which is a common experience in the use of the ordinary hook and eye. It is also apparent that by employing a plurality of 80 connected hooks and loops which are each formed from a single length of wire, that the necessity of resorting to numerous measurements in order to insure the proper placing of the loops with relation to the eyes, 85 upon opposite sides of the placket, is avoided, and it is simply necessary to place the first loops at the top of the placket in proper position with relation to the hooks when they may be laid upon the material 90 and quickly secured thereto without further measurement. As the device is of very simple construction, it will be obvious that the same can be produced at comparatively 95 small cost.

While I have shown and described the preferred form and arrangement of the parts, it will be obvious that the same are susceptible of considerable modification without departing from the essential features or sacrificing any of the advantages of the invention.

Having thus described the invention, what is claimed is:

A fastener of the character described comprising a hook formed from a single length of wire, said hook having a bill and a resilient locking tongue opposed to the bill, the intermediate portion of said tongue being adapted to rest against the free end of the bill, the extremity of the tongue extending obliquely from the free end of the bill to the forward end of the hook, and a loop also formed from a single length of wire, the wire of the loop being bent upon itself at the 115 ends of the loop to form attaching eyes, the intermediate portion of the wire of the loop being bent inwardly to rest against the wire of the bill and then offset at right angles to the plane of the body portion of the loop, the 120 offset portion of the loop being of a length substantially the distance between the hook bill and the offset portion of the loop, and 125

being adapted to extend entirely across the space between the hook bill and the body portion of the loop when said loop and hook are connected, said resilient locking tongue 5 bearing against the cross bar of the offset portion of the loop and adapted to normally hold the hook against rocking movement upon the loop.

In testimony whereof I hereunto affix my signature in the presence of two witnesses. 10

MARY A. WILLBRANDT.
